UNITED STATES PATENT OFFICE.

ELMER C. VEZIE, OF WASHINGTON, PENNSYLVANIA.

PUMP-PISTON.

1,162,265.

Specification of Letters Patent. Patented Nov. 30, 1915.

Application filed July 6, 1914. Serial No. 849,042.

To all whom it may concern:

Be it known that I, ELMER C. VEZIE, a citizen of the United States, residing at Washington, in the county of Washington and State of Pennsylvania, have invented a new and useful Pump-Piston, of which the following is a full, clear, and exact description, reference being had to the accompanying drawings, in which—

10 Figure 1 is a longitudinal section of a portion of a pump barrel and piston, and showing my invention. Fig. 2 is a similar view with the packing sleeve of the piston expanded. Fig. 3 is a side elevation of the 15 end portion of the piston, and Figs. 4 and 5 are sections taken respectively on the lines IV—IV and V—V of Fig. 1.

My invention has relation to pump pistons, and is designed to provide an improved 20 arrangement of the piston packing, whereby a tight joint is at all times insured between the piston and pump barrel or cylinder without the use of cup leathers or washers, such as are commonly used.

25 In accordance with my invention, I provide the piston with an extended packing sleeve of any suitable flexible material; and also provide means whereby the pressure of the fluid being pumped is made available to 30 hold this packing sleeve in its distended packing position.

My invention is applicable to various forms and classes of pumps, the particular form shown in the drawing being merely 35 illustrative of one embodiment of my invention.

In the drawings, the numeral 2 designates a portion of a pump barrel or cylinder and 3 the piston rod.

40 4 is a packing sleeve of any suitable flexible material which is seated around the lower end portion of the piston rod between suitable confining members at its ends, such as the sleeves or ferrules 5. One of these 45 sleeves or ferrules is made removable and may be screwed upon a threaded portion 3^a of said rod. Secured on the end of the rod, preferably by screwing it on the threaded portion 3^a of the rod against the end of the 50 adjacent ferrule 5, is an end piece or head 6 having preferably a plurality of inlet openings 7. These inlet openings extend into an internal chamber 8 of the head, said chamber having a valve seat at 9 controlled 55 by an inwardly opening check valve 10 of any suitable character. The portion 3^a of

the piston rod has a longitudinal internal port 11 communicating with the chamber 8 and also having one or more radial openings 12 which extend out through its peripheral 60 wall so as to conduct the fluid directly against the inner surface of the packing sleeve 4.

It will be readily seen that on each alternate stroke of the piston, the valve 10 will 65 be opened by the opposing pressure of the fluid being pumped, thereby admitting such fluid to the interior of the chamber 8 and into the port 11 until such chamber and port are completely filled. On the reverse strokes 70 the check valve is seated, thus confining the fluid. In this manner the pressure of the fluid is made available at all times to hold the packing sleeve in a distended position such as illustrated in Fig. 2. The packing 75 can thus be used until it is worn very thin without its efficiency being materially impaired.

It will be obvious that the particular construction and arrangement of the various 80 parts may be varied considerably in the application of the invention to various forms of pumps and pistons, within the scope of the appended claims.

I claim:

1. A pump piston having an expandable packing sleeve on the outer surface thereof, means for tightly securing both ends of the sleeve to the piston, there being a chamber within said piston having fluid under pressure therein, ports connecting the pressure chamber with a space between the sleeve and the piston whereby the packing sleeve is normally expanded, there being a port communicating with said chamber and a check valve in said port for admitting and retaining fluid under pressure in said chamber; substantially as described.

2. A pump piston having an expandable packing sleeve on the outer surface thereof, means for securing both ends on the sleeve to the piston, there being a pressure chamber within the piston, ports connecting the pressure chamber with a space between the sleeve and the piston, and means for admitting and retaining fluid under pressure within said chamber whereby the packing sleeve is normally expanded; substantially as described.

3. A pump piston having an expandable packing sleeve on the outer surface thereof, ferrules for connecting the ends of the sleeve

to the piston, there being a pressure chamber within said piston closed at one end, ports connecting the pressure chamber with a space between the sleeve and the piston, there being an opening at the other end of said chamber for admitting fluid under pressure to said chamber, and a check valve for controlling the admission of said fluid and retaining it within said chamber; substantially as described.

4. The combination of a force pump having a barrel or cylinder and a piston rod within said barrel, said piston rod having an expansible packing sleeve surrounding it, means for connecting both ends of said sleeve to the piston rod to form air tight joints between the ends of the packing sleeve and the piston rod, there being a pressure chamber within said piston rod, said pressure chamber being closed at one end and open at the end toward the pump chamber,

ports connecting the pressure chamber with the space between the sleeve and the piston, and a check valve for controlling the opening leading to said pressure chamber, said check valve being arranged to be opened on the inward stroke of the piston to force fluid into the pressure chamber and the space between the piston rod and the packing sleeve, said check valve being also arranged to retain said fluid under pressure within the pressure chamber to normally hold the packing sleeve against the pump cylinder to maintain a tight joint between the packing sleeve and the pump cylinder; substantially as described.

In testimony whereof, I have hereunto set my hand.

ELMER C. VEZIE.
